UNITED STATES PATENT OFFICE.

EUGENE W. HAWLEY, OF PHILADELPHIA, PENNSYLVANIA.

TRUNK-LOCK.

1,266,939.

Specification of Letters Patent. Patented May 21, 1918.

Application filed November 15, 1916. Serial No. 131,389.

To all whom it may concern:

Be it known that I, EUGENE W. HAWLEY, a citizen of the United States, residing at Philadelphia, county of Philadelphia and 5 State of Pennsylvania, have invented a new and useful Improvement in Trunk-Locks, of which the following is a full, clear, and exact description, reference being had to the accompanying drawings, which form a part 10 of this specification.

The object of my invention is to secure together the two members of a trunk by means of pairs of complementary locking members at several points along the length of the 15 trunk and operable from a single member, such as a hasp. More specifically, the objects of the invention are: to insure accurate and certain engagement between the locking members of each pair, to provide a double 20 stop to with more certainty insure that the movable locking members will operate only within prescribed limits, and to simplify the connection between the hasp and the movable locking members.

25 A preferred embodiment of my invention is shown in the accompanying drawings in which—

Figure 1 is a front view of a wardrobe trunk containing my invention. Fig. 2 is 30 a sectional elevation through the two sections of the trunk, the locking mechanism being shown in elevation. Fig. 3 is a detail view of a pair of locking members and the actuating mechanism for operating the 35 movable member with the parts in unlocked position but ready for engagement. Fig. 4 is a detail view of the actuating mechanism shown in Fig. 3 but moved into position to effect engagement between the locking members. Fig. 5 is a horizontal cross section 40 through the two locking members. Fig. 6 is a section on the line 6—6 of Fig. 3.

The trunk comprises two sections *a* and *b* hinged together in the usual way. The trunk 45 is shown in an upright position, as it is intended to illustrate that type of trunk known as a wardrobe trunk. On the outside of one trunk section *a* is pivoted, on a horizontal axis, a hasp support *c*, to which is pivoted, 50 on a vertical axis, the hasp *d*, which is adapted to swing into engagement with a socket *e* on the other trunk section *b*.

The turnable pivot of the hasp support *c* extends through the wall of the trunk and 55 on the inside thereof carries the disk *f*

(which is in effect a crank arm) and a stop *g*.

Slidable vertically in guides *j* on the inner wall of trunk section *a* is a bar *i*. Connecting the bar *i* and a pin on the disk *f* is 60 a rod *h*.

The bar *i* has secured to it a plurality of locking members having upwardly-extending wedge-shaped projections *k*. The inner wall of the section *b* has secured to it a plurality of locking members *m* having sockets adapted to receive the projections *k*. The sockets of members *m* are provided preferably with wedge-shaped end walls corresponding in contour to the contour of projections *k*, although this feature is not essential, as if one locking member is wedge-shaped, the function sought will be accomplished. The sockets of members *m* are also provided with side walls, into which the 70 projections *k* neatly fit, thereby insuring the perfect alinement of the two trunk sections when they are interlocked. To insure the entry of the projections into the sockets, the side walls of the projections *k* are tapered 75 upwardly as shown in Fig. 6.

The mode of operation of the locking device is as follows:

Assume that the trunk is open and that the hasp *d* is swung into an approximately 80 vertical position, as shown in Fig. 3. To close and lock the trunk, the trunk sections are first swung toward each other so as to bring their opposing vertical edges into approximately close engagement. The hasp *d* is 85 then swung, on its horizontal pivot, from the position shown in Fig. 3 to the position shown in Fig. 4. This movement, through the medium of disk *f* and connecting rod *h*, draws up the bar *i*, causing the projections 90 *k* to enter the sockets of members *m*. If the two trunk sections are not in exact alinement, the tapered end of each projection *k* will nevertheless enter its corresponding 95 socket and draw the trunk sections into exact alinement as the bar *i* moves up. At the same time, owing to the wedge-like engagement between the two locking members, the two trunk sections will be drawn more tightly together. The hasp *d* is then swung 100 on its vertical axis into engagement with the socket *e*.

It will be observed that the movement of the bar *i* is exactly parallel to the direction of its extension. When the bar *i* is moved 105

up into the locking position shown in Figs. 2 and 4, its movement, when the hasp *d* reaches the horizontal position necessary for its subsequent engagement with the socket *e*, 5 is arrested by a double stop. In the first place, one of the flat faces of the stop *g* contacts with the straight edge of the connecting rod *h*. In the next place, one of the movable locking members *k* contacts with 10 one of the guides *j* for the bar *i*. Conversely, when the bar *i* is moved down away from the locking position into the unlock- 15 ing position shown in Fig. 3, its movement is arrested, first by contact of stop *n* on the rod *h* with the bar *i* and again by the contact of another locking member *k* with another guide *j*. This double stop is important in that in the event of wear and tear of either part, and particularly lost motion 20 arising therefrom in the hasp connections, the other lock will be effective. The direct lock for the bar is conveniently arranged without the provision of any extra parts by locating two of the guides *j* between two of 25 the movable locking members *k*.

It will also be observed that in its locking movement the bar *i* moves up and not down. This is advantageous as the locking operation involves a pull away from floor and 30 not a push against the floor, thereby enabling the locking operation to be effected with substantially less muscular force.

Having now fully described my invention, what I desire to claim and protect by Letters Patent is:

1. In a trunk, the combination with the two hinged sections thereof, of a main locking device pivoted to one section, a bar 40 slideable on the same trunk section longitudinally of the trunk, connections between the main locking device and the bar to convert a turning movement of the former into a longitudinal movement of the latter, fixed locking members on the other trunk section 45 each comprising a relatively long and narrow socket and complementary locking members secured to the bar each comprising a flat and relatively thin projection adapted to engage the corresponding socket, the locking members of each complementary pair 50 having an inclined edge adapted to engage one end of the corresponding socket to draw the two sections toward each other, the side walls of each projection being beveled adjacent its end and the side walls of the socket flaring outward adjacent its mouth to draw 55 the two sections into exact alignment.
2. In a trunk, the combination with the

two hinged sections thereof, of a main locking device pivoted to one section, a bar slideable on the same trunk section longitudinally of the trunk, connections between the main locking device and the bar to convert a turning movement of the former into a longitudinal movement of the latter, two 60 fixed locking members on the other trunk section, two complementary locking members on the bar, and guides for the bar on the first trunk section, two adjacent guides being spaced apart a shorter distance than, 65 and located between, two adjacent movable locking members and thus acting as stops one to arrest the movement of the bar in one direction and the other to arrest the movement of the bar in the other direction. 70

3. In a trunk, the combination with the two hinged sections thereof, of a main locking device pivoted to one section, a crank arm and a stop secured to and turning with the main locking device, a bar slideable on 80 the same trunk section longitudinally of the trunk, a connecting rod pivoted both to the bar and to the crank arm, fixed locking members on the second trunk section, complementary locking members secured to the 85 bar, guides for the bar on the first trunk section, and a stop on the connecting rod, the first stop adapted to contact with the connecting rod and thereby limit the movement of the bar in one direction and the 90 second stop adapted to contact with the bar and limit its movement in the opposite direction.

4. In a trunk, the combination with the two hinged sections thereof, of a main locking device pivoted to one section, a bar slideable on the same trunk section longitudinally of the trunk, connections between the main locking device and the bar to convert a turning movement of the former into a 100 longitudinal movement of the latter, fixed locking members on the other trunk section, complementary locking members on the bar, stops movable with the main locking device and adapted to arrest the movement of the 105 main locking device and bar in opposite directions, and guides for the bar on the first trunk section adapted to contact with the movable locking members, and arrest their movement and consequently the movement of the main locking device and bar in 110 opposite directions.

In testimony of which invention, I have hereunto set my hand, at Philadelphia, on this seventh day of November, 1916.

EUGENE W. HAWLEY.
